(57) **CLAIM**

The ornamental design for a spherical lid, as shown and described.

DESCRIPTION

FIG. 1 is a front perspective view of a spherical lid showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the spherical lid shown in FIG. 1 in the environment of a lipstick;

FIG. 9 is a front view thereof;

FIG. 10 is a back view thereof;

FIG. 11 is a left side view thereof;

FIG. 12 is a right side view thereof;

FIG. 13 is a top view thereof;

FIG. 14 is a bottom view thereof;

FIG. 15 is a front perspective view of the spherical lid shown in FIG. 8 in the environment of a lipstick case; and,
FIG. 16 is a front perspective view of the spherical lid shown in FIG. 8 in the environment of a perfume container.

The broken lines shown from FIGS. 1-7 represent parts of the article that form no part of the claim. The broken lines shown from FIGS. 8-16 represent environmental subject matter of an exemplary lipstick, lipstick case, and perfume container that form no part of the claim.

The applied surface pattern in the drawings represents contrasting appearance.

1 Claim, 10 Drawing Sheets
